ACTUATING CONSTRUCTION

Werner Robert Bauer, Columbus, Ohio, assignor to Robertshaw Controls Company, Richmond, Va., a corporation of Delaware

Filed Apr. 16, 1964, Ser. No. 360,369

5 Claims. (Cl. 200—83)

This invention relates to an actuating construction, such as a switch for controlling the water filling valve of the tub of an automatic washing machine to obtain various selected fill water levels in the tub. However, the invention may be applied to other switches for controlling other operations, as is apparent.

A feature of this invention is that, in all adjustment positions of the switch, the adjustable disc or nut that receives one end of the controlling or loading pressure spring remains substantially parallel to and aligned with the spring receiving surface of the switch actuating member, which receives the other end of the loading spring.

Another feature of this invention is that such spring end receiving disc or nut may be used as the sole rotatable calibrating member, which remains substantially aligned and in a selected calibrated position without the use of lock nut and the like.

Another feature of this invention is that such adjustable spring end receiving disc or nut may be rotatably calibrated about a pivoted screw construction by hand or by a simple tool and without the use of a lock nut, and will remain in the calibrated position without the likelihood of being moved from such calibrated position during subsequent use.

Other features of this invention are apparent from this description, the appended claimed subject matter, and/or the accompanying drawings, in which:

FIGURE 1 is a side elevation, partly in cross section, of a switch embodying this invention.

FIGURE 2 is an enlarged vertical cross section of a portion of FIGURE 1.

FIGURE 3 is a perspective view of the adjusting lever and its supporting bracket.

FIGURE 4 is a perspective view of the upper end of the disc receiving screw construction before attachment to the adjusting lever.

FIGURE 5 is a vertical cross section showing the attachment of the upper part of FIGURE 4 to the inverted channel construction of the adjusting lever shown in FIGURE 3.

FIGURE 6 is a perspective view showing another embodiment of a construction for the pivot construction at the upper end of the screw shown in FIGURE 4.

FIGURE 7 is a vertical cross section similar to FIGURE 5, but taken along the vertical plane of line 7—7 of FIGURE 6.

FIGURE 8 is a chart showing advantages of the embodiments of FIGURES 1-7 as compared to the switch construction of FIGURE 9.

FIGURE 9 is a view of a pressure adjusting lever somewhat similar to that shown in FIGURE 1, but not having the pivotal advantages of the disc supporting screw of FIGURE 1.

FIGURE 10 is a vertical cross section showing the spring ends of a compression coil spring which may be used with the switch of this invention.

This invention is applicable to many switches of all kinds, such as water level switches to be used in combination with automatic washing machines, and the like. Merely by way of example, the invention may be applied to a water level switch of the character disclosed in the patent to Clark et al., No. 2,636,093, patented April 21, 1953, which, for brevity, will be hereafter referred to merely as the Clark patent. However, the invention may

2

be applied to other water level switches, other switches of any kind, and other pressure responsive switches and the like. The Clark patent is used merely as an example of such other switches.

5 Certain directionally indicating words are used in this application, both in the specification and in the claims, which words indicate direction, relative position, and the like. These words are used for brevity and clearness in description of the various parts as they are illustrated in the drawings. However, it is to be understood that in actual use and construction, the various elements described with such directionally indicating words may have entirely different directions and relative positions, since such switch construction, in actual use, may be inverted, used horizontally instead of vertically, etc. However, these direction indicating words used in the specification and claims of this character are intended to be interpreted merely to indicate relative positions between the various members described, if the actual article were 10 placed in the position shown in the drawings, for the purpose of comparison, although such article actually may be placed or used in any other position. Examples of such words are "vertical," "horizontal," "upper," "lower," and the like.

15 Referring first to FIGURE 1, a typical pressure switch construction 10 is shown partly in side elevation and partly in cross section. This construction may include a pressure responsive snap switch containing casing having an upper part 12 and a lower part 14, such as shown in 20 said Clark patent. This casing may contain a snap switch 16, a water level pressure responsive diaphragm 18, which snaps the switch 16 back and forth in response to pressures produced in the tube 20. Such switch may be connected to a washing machine tub in a manner to be responsive to the level of the water in the tub, as is well known. The diaphragm 18 may actuate the switch 16 by means of an actuator or upwardly directed actuating member 22, the upper end of which may be directly or 25 indirectly connected to the upwardly directed switch actuating shiftable spring base 24. This spring base 24 may have a generally flat spring receiving upper end 46. The spring base 24 may extend upwardly through the upper wall 26 of the casing part 12. All of the foregoing elements may, if desired, be similar to those disclosed in the 30 Clark patent, although they may vary from the disclosure in the Clark patent, as is obvious.

35 An upwardly directed switch loading compression coil spring 28, with upper and lower ends, may have its lower spring end engaging the shiftable spring base 24.

40 A spring adjusting lever 30 may be generally horizontally disposed adjacent to and above the coil spring 28, so that it is transverse to such coil spring. The lever 30 may be pivoted or otherwise supported on the casing, such as on casing part 12. The lever 30 may have a 45 downwardly directed transverse channel construction at 32.

45 A vertical screw member 34 may be provided, which has its lower screw end in the coil spring 28. The screw member also has a transverse pivot member 36 at its upper screw end with a horizontal edge construction 38 upwardly engaging the inverted "bottom" of the downwardly directed or inverted transverse channel construction 32.

50 An upper spring end receiving nut or disc 40 may be 55 frictionally threaded on the screw member 34, so that it resists turning movement, and yields only to a relatively strong adjusting turning action.

60 For this purpose the screw 34 and the disc 40 may both be made relatively thick so that a relatively long and large diameter threaded connection is provided to impart a relatively strong frictional engagement between the screw 34 and disc 40.

The nut 40 may have a coil receiving flat surface 42, for receiving the upper end of the spring 28. The frictional turning torque required to turn the disc 40 is made greater than the frictional turning torque between the spring 28 and the spring receiving surface 42. Hence, no turning movement of the spring 28 will turn or change the adjustment of the nut 40. No lock nut is required to maintain the nut 40 in its adjusted position. The rim of the nut 40 may be fluted at 41 for manual adjustment of the nut 40.

The shiftable spring base 24 may move up and down in response to the movements of the diaphragm 18. It may be directly or indirectly connected to the actuating member 22. It may have its upper end received in an upwardly directed casing flange 44 of the upper wall 26 of the casing part 12. Such spring base 24 may be made of nylon and may have a generally flat horizontal surface 46 with a vertical spring holding flange construction 48, which may be in the form of a short cylindrical extension 49 to the spring base 24.

Both the spring base 24 and the nut or disc 40 may be made of a relatively low friction material, such as nylon, so that any turning movements of the spring 28 produced during its compression and expansion of such spring 28 cannot impart any strong turning movement to the nut or disc 40, since such disc 40 is threaded to the screw 34 with relatively long and tight fitting threads. Hence the torque required to turn or displace the disc 40 from its adjusted position and the like will be much greater than any turning movement that can be produced by the spring 28. That is, the friction of the end of the spring 28 on the disc 40 is much less than is necessary to turn or displace such disc about the screw 34 from its adjusted position. Therefore, the disc 40 will remain in calibrated position, without the use of a lock nut, during subsequent use of the switch.

The nut or disc 40 need not be adjusted with aid of any screw driver and wrench, or the like, to tighten a lock nut. Instead, it can be adjusted manually or with any friction type of pincers or the like, and will remain in adjusted position without any lock nut.

The inverted channel construction 32 and the pivot member 36 prevent the screw 34 from turning while the nut 40 is being adjusted yet permit the screw to pivot to maintain the nut 40 parallel to and substantially aligned with the spring base 24.

The nut or disc 40 may have a downwardly directed vertical spring holding flange construction 50 and 52. Such flanges 50 and 52, with the flat surface 42 produce a downwardly directed groove for receiving the end of the spring 28. This groove construction holds the upper end of the spring 28 from accidental lateral displacement from under the disc 40.

The downwardly directed or inverted transverse channel construction 32 of lever 30 may include two spaced downwardly directed channel members 54 and 56, FIGURE 3, with an opening 58 between them. The transverse pivot member 36, FIGURE 4, has an upwardly directed central extension 60, which is located in the opening 58 between the downward channel members 54 and 56. The central extension 60 may have two upward tongues 62 which may be laterally bent over the channel members 54 and 56, as indicated at 62' in FIGURE 5, to engage and secure the transverse pivot member 36 to the members 54 and 56 by engagement with the upper surfaces of the channel members 54 and 56. The engagement of the tongues 62 with the members 54 and 56 may be sufficiently loose to permit a pivoting movement between the screw 34 and lever 30.

The transverse pivot member 36 may be firmly secured in a groove 64 at the upper end of the screw 34. The member 36 may be secured in the groove 64 by a welding or soldering operation, or the like, as desired.

The lever 30 may have downwardly extending flanges 66 for strengthening purposes and the like.

The transverse pivot member 36 may be modified, as indicated at 36A in FIGURES 6 and 7. The transverse member 36A may have two upwardly directed extensions 60A, each with a tongue 62A. These tongues 62A may respectively extend through upward openings 58A in each of the two spaced downwardly directed channel members 56A and 54A. Otherwise, the parts of FIGURES 6 and 7 may be substantially the same as those shown in FIGURES 1 through 5.

While the snap switch 16, the diaphragm 18, the actuator 22 and the spring base 24 have been shown as somewhat similar to those disclosed in the Clark patent, and may operate substantially in the same manner as in the Clark patent, it is to be understood that any other type of switch construction may be placed in the casing 12, 14, and that the casing 12, 14, itself, may have any desired shape, which may be different from that disclosed in the Clark patent. Under certain conditions the casing may be omitted.

20 The lever 30 may be pivoted at 70 on a bracket 68. Any suitable type of pivot joint 70 may be provided between the lever 30 and the bracket 68, which is secured to wall 26 by the flange 69. For example, the end of the lever 30 may have a notch 72. The upper end of 25 the bracket 68 may have a receiving notch 74, so that the lever 30 and the bracket 68 may be joined together by relative longitudinal movement between the lever 30 and the bracket 68, or vice versa, to form the pivot or joint 70. The other end of the lever 30 may have a 30 pointed end 76. The pointed end 76 may be inserted in a slot 78 of a U-shaped bracket 80 which may be secured to the top surface 26 by means of a screw 82, which passes through the horizontal bracket bottom member 83.

The upper ends of the U-shaped bracket 80 may receive a rotatably adjusting shaft 84. Any type of cam construction 86 may be placed on shaft 84, which cam may have a gradual cam operating surface, or a plurality of lobes which can push down the lever 30 as far as is desired to adjust the loading tension of the spring 28 and 35 to select any one of a plurality of water levels to be produced in the washing machine tub, as is well known. The left end of shaft 84 may be provided with any type of operating member, not shown, such as a knob or operating lever. For example, the cam 86 may adjust the switch 40 construction to provide "low," "medium," and "high" 45 water fill levels in the tub of the washing machine.

If desired, an auxiliary compression coil spring 88, FIGURE 1, may have its upper end surrounding a downward flange 90 of lever 30, to hold the upper end of the spring 88 against lateral displacement. The lower end of the spring 88 may be received in a slight depression 92, to hold the lower end of the spring 88 against lateral depression. The spring 88 provides auxiliary or additional upward force to the lever 30. Such spring 88 may be 50 used whenever the compression spring 28 does not have the desired amount of upward force to maintain the lever 30 firmly locked at the joint 70 and firmly held against the cam surface of the cam construction 86. However, if the compression spring 28 has sufficient upward strength, then the spring 88 may be omitted.

FIGURE 8 is a chart to illustrate certain forces which cause the construction of this invention to be very valuable in maintaining a uniform response of the compression spring 28 to the action of the diaphragm 18 in spite of the usual variations produced during manufacturing steps. 55 Previous manufacturing steps or procedures have created an undesirable variance from the theoretical desired response of the spring to the operating pressures during use of the switch construction, as will be further explained.

For example, FIGURE 9 shows a type of construction in which undesirable variations may be produced in the responsiveness of the compression spring to the pressures of the diaphragm of the switch.

The lever 30B of FIGURE 9 may correspond to lever 70 75 30 of FIGURE 1. However, instead of the pivoted screw,

34 of FIGURE 1, the unpivoted screw 34B of FIGURE 9 may be fixedly secured to the lever 30B. The nut 40B may be frictionally threaded on the screw 34B so that its spring receiving surface 42B (corresponding to surface 42 of FIGURE 2) is in a slanting position with respect to the horizontal surface 46B of the spring base 24B, as shown in the unbroken line position of FIGURE 9.

However, with applicant's construction of FIGURE 1, the spring receiving surface 42 is maintained substantially parallel to the flat surface 46 of the actuator, so that it makes no difference where the wire ends 104 and 105, FIGURE 10, of the spring 28 contact the disc 40 and the actuator surface 46, since one side of the spring is not flexed more than the other side, as will be pointed out in connection with FIGURE 8.

Additionally, the fulcrum point 110, FIGURE 1 and FIGURE 2, is placed relatively far from the surface 46, so that there is substantially no unequal flexure of the spring as is produced where disc 42B of the spring construction is below the lever 30B, as is shown in FIGURE 9. There is no fulcrum with the lever 30B, in FIGURE 9, which aggravates any misalignment which may be produced by the arc movement of the levers 30 and 30B about the respective joints 70 and 70B.

FIGURES 1 and 9 show the corresponding levers 30 and 30B in the "low" setting of the switch. In this position, the snap switch 16 will close a solenoid water valve to stop the supply of water to the washing machine tub at a "low" fill level, such as indicated at X" in FIGURE 8. The levers 30 and 30B are slanting upwardly toward their left ends 76 and 76B. The lower surface 42 of the nut 40 is parallel to the horizontal surface 46 of the spring base 24, as shown in FIGURES 1 and 2, whereas the lower surface 42B of nut 40B of FIGURE 9 is slanting with respect to the horizontal surface 46B of spring base 24B. Under these conditions, the spring 28 of FIGURE 1 is uniformly compressed completely around its circumference. However, spring 28B of FIGURE 9 is compressed more on its right side than it is on its left side, as is illustrated in FIGURE 9. It will become apparent that a variation in the responsiveness of the spring 28B will occur if its upper wire end 104, FIGURE 10, is near its left side 104 or its right side 106. (The same is true of the lower wire end 105.) It will also become apparent that such wire end 104 (or 105) may be placed anywhere around the circumference of the coil receiving surface 42 or 42B. Also it will become apparent that the springs 28 and 28B can rotate intermittently slight amounts during each compression and expansion of such springs. This is a cumulative action produced each time the tub is filled and emptied. This may produce complete rotation of such springs during the use of the switches. However, the nut 40 of FIGURE 1 remains substantially parallel and aligned under all its operating conditions whereas the nut 40B is generally slanting, and varies its slanting conditions during adjustment of water levels by cam 86. This causes the switch of FIGURE 1 to remain substantially uniformly responsive under all manufacturing procedures, and during its later use, whereas the switch of FIGURE 9 is subject to wide variations both during manufacturing procedures and during its subsequent use.

When the switches of FIGURES 1 and 9 are adjusted by the user to the "high" fill positions, their levers 30 and 30B, screws 34 and 34B and discs 40 and 40B, move to the dotted lines indicated by the letter "H" in FIGURES 1 and 9. Only a minimum of lines "H" are indicated to prevent confusion in such FIGURES 1 and 9. In FIGURE 1, the top of the channel member 32 is also shown in dotted lines and is marked H to show that substantially no misalignment of the screw 34 and nut 49 with the spring base 24 takes place, whereas a marked misalignment of the screw 24B and nut 40B does take place. The slants of screw 34B and nut 40B have been reversed in the "high" position as compared to their "low"

position. This likewise reverses their relationship to the wire ends 104 and 105 of FIGURE 10.

A similar factor of spring irregularity exists with respect to the lower wire end 105 of the coil springs 28 and 28B and also causes wide variations in the embodiment of FIGURE 9 but substantially no variations in the embodiment of FIGURE 1.

FIGURE 8 is a diagram intended to show the pressures produced between the members 24 and 40 at the "low," "medium" and "high" positions of the levers 30 and 30B when the levers 30 and 30B are adjusted by the selecting cam 86 and by manual rotation of the selection shaft 84. The horizontal lines 110, 111 and 112 show these respective fill positions and indicate that a water column

15 pressure respectively of X", Y" and Z" should be obtained at these positions when the snap switch 116 snaps to the water off position in response to the pressures produced through the tube 20 of FIGURE 1 by a rise in the height of the water in the washing machine tub respectively at the "LOW," "MEDIUM," and "HIGH" setting of the cam 86. Such pressures are the desired pressures substantially obtained by the embodiment of FIGURE 1, as indicated by the intersection of the heavy slanting line 114 respectively with the vertical lines 115, 116 and

20 117. However, in the case of the embodiment of FIGURE 9, because of the slanting variations of nut 40B and the rotation of the coil spring wire ends 104 and 105, erroneous variations can occur in the responsiveness of the spring 28B as indicated by the intersections of the

25 vertical lines 115, 116 and 117 with the slanting lines 118 or 119. For example, in the medium position, such embodiment of FIGURE 9 might produce either a water column pressure lower than Y" as shown at 120 or higher than Y" as shown at 122. Similar variations can occur at 125 and 126 in the "low" position and at 127 and 128 in the "high" position, and will be aggravated at such high position, as is obvious.

30 The vertical line 124 indicates the theoretical pressure of the spring 28 or 28B when fully expanded, which cannot take place when the spring is assembled in the switch but shows the length of the spring before assembly and before any compression thereon. The spring pressure at that position is zero inches of water column, and is therefore indicated as 0" on the chart of FIGURE 8.

35 The vertical line 130 indicates the theoretical pressure produced by the spring 28 or 28B just before it is fully compressed.

40 The intersections of the slanting dotted lines 118 and 119 with the vertical lines 115, 116 and 117 indicate the possible plus or minus errors in the pressures produced by the accidental rotation of the spring wire ends of

45 spring 28B. The intersections of the solid line 114 with the vertical lines 115, 116 and 117 indicate the desired pressures which are substantially obtained, without substantial errors, with the spring 28 of FIGURE 1 because of the superior construction of the support for the horizontal nut 40 as compared to the slanting nut 40B.

50 Spring pressure charts, similar to that shown in FIGURE 8, are well known to those skilled in the art of the use of springs for the purpose of actuating pressure responsive switches. Further description is, therefore, deemed unnecessary.

55 It is thus to be seen that a new, useful and unobvious switch construction has been provided by this invention.

56 While the form of the invention now preferred has been disclosed as required by statute, other forms may be used, all coming within the scope of the claimed subject matter which follows.

60 What is claimed is:

65 1. In combination: a construction having an upwardly directed actuating member with a flat end designed to receive a spring; an upwardly directed loading compression coil spring having a lower end engaging said upper flat end; a generally horizontal spring adjusting lever mounted on said construction and having a downwardly directed

transverse channel; a vertical screw member having a lower free end in said coil spring and having a transverse pivot member firmly secured at its upper end with a horizontal edge construction upwardly engaging said downwardly directed transverse channel the engagement of said transverse channel and said edge construction locking said screw member from turning; and a nut threaded on said screw member and having a generally horizontal flat surface receiving said upper flat end of said coil spring.

2. In combination: a pressure switch construction including a pressure responsive snap switch containing casing with an upwardly directed shiftable spring base extending through the upper wall of said casing; an upwardly directed switch loading compression coil spring having a lower end engaging said shiftable spring base and having an upwardly directed end; a spring adjusting lever transverse to said coil spring, pivoted on said casing and having a downwardly directed transverse channel; a vertical screw member having a lower end in said coil spring and having a transverse pivot member firmly secured at its upper end with a horizontal edge construction upwardly engaging said downwardly directed transverse channel the engagement of said transverse channel and said edge construction locking said screw member from turning; and a nut threaded on said screw member and having a coil receiving surface receiving the upper end of said spring.

3. In combination: a pressure switch construction including a pressure responsive snap switch containing casing with an upwardly directed shiftable spring base extending through the upper wall of said casing; an upwardly directed switch loading compression coil spring having a lower end engaging said shiftable spring base and having an upwardly directed end; a spring adjusting lever transverse to said coil spring, pivoted on said casing and having a downwardly directed transverse channel; a vertical screw member having a lower end in said coil

spring and having a transverse pivot member firmly secured at its upper end with a horizontal edge construction upwardly engaging said downwardly directed transverse channel, the engagement of said transverse channel and said edge construction locking said screw member from turning; and a nut threaded on said screw member and having a coil receiving surface receiving the upper end of said spring, and in which said downwardly directed transverse channel includes two spaced downwardly directed channel members and said transverse pivot member has an upwardly directed central extension located between said channel members.

4. A combination according to claim 3 in which said central extension has two upward tongues which are laterally bent over said channel members.

5. In combination: a pressure responsive switch with an upwardly directed actuating shiftable spring base; an upwardly directed compression coil spring having a lower end engaging said shiftable spring base and having an upwardly directed end; a spring adjusting lever transverse to said coil spring and having a downwardly directed transverse channel; a vertical screw member having a lower free end in said coil spring and having a transverse pivot member firmly secured at its upper end with a horizontal edge construction upwardly engaging said downwardly directed transverse channel the engagement of said transverse channel and said edge construction locking said screw member from turning; a nut threaded on said screw member and having a coil receiving surface receiving the upper end of said spring.
